MACHINE FOR MAKING TUBULAR PARTS FROM STRIP MATERIAL

August Viehweger, Comstock Park, Mich.

Application January 15, 1945, Serial No. 572,830

21 Claims. (Cl. 113—35)

1

This invention relates to improvements in machine for making tubular parts from strip material.

The main objects of this invention are:

First, to provide a machine for making tubes adapted for use in sash balances from strip stock.

Second, to provide a machine for making double ply tubes having spiral grooves from flat strip stock.

Third, to provide a machine of this character adapted to produce work of very uniform quality and work which is not likely to become distorted.

Fourth, to provide a machine for forming tubes of spirally coiled strips in which the stock is "set" as the coiling proceeds.

Fifth, to provide a machine for forming tubes from spirally coiled flat stock which owing to the character of the forming dies and the manipulation thereof enables the coiling of the stock with a minimum of stress thereon and on the machine parts.

Sixth, to provide a machine of the class described which is of large capacity.

Objects relating to details and economies of the invention will appear from the description to follow. The invention is defined and pointed out in the claims.

A preferred embodiment of the invention is illustrated in the accompanying drawings, in which:

Fig. 1 is a fragmentary plan view of a structure embodying the features of my invention, certain of the parts being shown mainly in conventional form.

Fig. 2 is a view partially in vertical section on the broken line 2—2 of Fig. 1.

Fig. 3 is a fragmentary plan view partially in section on line 3—3 of Fig. 4 illustrating certain of the coiling operations and the relationship of the stock thereto.

Fig. 4 is an enlarged fragmentary view on line 4—4 of Fig. 3.

Fig. 5 is an enlarged fragmentary view on line 5—5 of Fig. 3.

Fig. 6 is a fragmentary view in section on line 6—6 of Figs. 4 and 5.

Fig. 7 is an enlarged fragmentary sectional view on line 7—1 of Fig. 3.

Fig. 8 is a fragmentary view partially in section on line 8—8 of Fig. 3 showing the relation of the completed tube to the mandrel.

Fig. 9 is a detail sectional view on line 9—9 of Fig. 1.

Fig. 10 is a fragmentary view of a completed section of work.

Fig. 11 is an elevation of a portion of die 15.

In the accompanying drawings, the table or bed 1 is of suitable dimensions to support the operating parts of the machine. This is com-

monly supported upon suitable legs and provided with other supporting means not illustrated.

The machine illustrated is designed to produce tubular members 2 having spiral grooves 3 and 4, the groove 3 being formed in the outer element 5 of the tube, the groove 4 being formed by the spaced edges 6 of the outer element 5 and bottomed by the inner element 7 of the tube. These elements 5 and 7 are formed from strips 10 of steel stock designated A and B.

The supporting pedestal 8 is provided with a head piece 9 at its forward end receiving the forward end of the mandrel 10 which is provided with a head portion 11 adapted to sustain the longitudinal pull thereon and the set screw 12 which prevents rotation of the mandrel.

Mounted on the pedestal is an anvil forming die member 13 having a transversely curved longitudinal die face 14 concentric with the mandrel 10. This die member 13 in the embodiment illustrated has a yieldably supported section 131 mounted on rods 132 carrying the springs 133 acting to urge the die members together. The segment 141 of the die face 14 on section line 131 is complementary to the portion of the die face formed on the stationary portion of the die member 13. The coacting die member 15 has a transversely curved longitudinal die face 16 complementary to the die face of the anvil forming die member and concentric to the mandrel as clearly shown in Figs. 4 and 5.

The purpose of providing the yieldingly supported portion 131 for the die member 13 is to permit a slight yielding as the stock is fed around the mandrel, requiring less thrust in feeding or advancing the stock than would otherwise be the case and preventing any kinking of the stock. The faces of the die members are preferably stepped as clearly shown in Figs. 3 to 6 to accommodate the second or outer strip of stock. This stepping of the die members would not be required where the machine is designed to spirally wind a single strip of stock.

The thrust die member 15 is provided with a crosshead 17 reciprocatingly mounted on the upright posts 18 carried by the bed 1, springs 19 acting to return the reciprocating die member to open position.

The reciprocating die member is actuated from the lever 20 pivoted at 21 on the vertically adjustable upright or support 22 and actuated from the crank 23 provided with a connecting rod or pitman 24 having a pivoted link 25 at its outer end, the link receiving the end of the lever 20 and being provided with a roller 26.

The stock strips A and B are fed in laterally spaced relation to each other and at an angle substantially less than a right angle relative to the mandrel and die members.

The feed means in the embodiment illustrated

comprise pairs of feed rollers 27 and 28, only one roller of each pair being illustrated, the driven rollers of the pairs being connected by the belt 29. The driven roller 28 is driven through a friction clutch 30 in the shaft 31, this shaft being 5 connected by a train of gears designated generally by the numeral 32, see Fig. 1, to the shaft 33 on which the crank 23 is mounted, this shaft 33 being connected by the pulley 34 and the belt 35 to the pulley 36 of the motor 37. A balance wheel 38 is provided for the shaft 33.

In the embodiment illustrated the driven rollers 27 and 28 are provided with annular ribs 39 which form a longitudinal groove 40 in the stock strip B prior to the feeding thereof to the forming dies. The die members in effect constitute coiling blocks as well as forming dies, the stock being fed against the die face 16 of the reciprocating forming die in impinging relation thereto. The frictional feed of the rollers on the stock is such that the stock is advanced when the reciprocating forming die is retracted. The feed is aided by a pull on the work as will be hereafter described.

To assist in conforming the work and to give it a permanent "set" as it is coiled, the reciprocating die imparts thrust-like blows to the work and this feature greatly aids in the spiral coiling of the stock.

The stock is fed to the mandrel and the dies at such angle as to provide a spiral groove between the edges of both strips and the strips are so spaced and fed to the mandrel and forming dies that the outer strip breaks joints with the inner strip, or rather with the spirals formed by the inner strip, with the rib resulting from forming the groove 40 between the spaced edges 41 of the inner strip, the spaced edges of the outer strip forming a second spiral groove bottomed by the inner strip, see Fig. 8.

To further set and size the work I preferably provide a follower die consisting of the members 42 and 43, see Fig. 7, the member 43 having a segmental curved conforming face 44 while the member 42 is provided with a plurality of work supporting rollers 45 which rotatably support the work while it is being sized and further set by the follower die.

At the rear of the follower die I provide supporting rollers 46 adapted to rotatably support the work and at the rear of these supporting rollers, at least one of which is driven, I provide a co-acting pair of grooved pull rollers 47 adapted to embrace the work while it is supported by the mandrel and impart a longitudinal pull thereto while permitting its rotation. These pull rollers also serve the purpose of holding the work against the supporting rollers 46.

The upper roller 47 is provided with a shaft 48 which is connected by the beveled gears 49 to the shaft 50 which is in turn provided with a beveled gear 51 meshing with the gear 52 on the shaft 53 connected by the gear 54 to a gear 55 on the shaft 31. This insures the driving of the pull rollers in synchronism with the feed rollers.

One of the rollers 46 is driven from a gear 56 connected to the shaft 48 by means of coacting beveled gears 57, see Fig. 1. The cams 58 are provided for releasably holding the stock driving rollers 27 and 28 to the stock and permitting the separation from their coacting rollers to permit introduction of the stock.

I have illustrated and described my invention in a highly practical embodiment thereof. I have not attempted to illustrate or describe various

embodiments or adaptations which I contemplate and which are possible as it is believed this disclosure will enable those skilled in the art to embody or adapt my invention as may be desired.

While the machine illustrated is especially designed for forming tubes of two strips of stock, it may be readily adapted for spirally coiling a single strip of stock into a tube.

In the manufacture of tubes for sash balances, it is desired to provide structures which will not spring or warp or distort or buckle in use and also tubular elements which are relatively light in weight and at the same time rigid. I can readily produce such elements on my machine and this with a machine of comparatively light weight and requiring but little power to operate. The disclosure made will enable the embodiment of my invention as may be desired.

Having thus described my invention, what I claim as new and desire to secure by Letters Patent is:

1. In a machine of the class described, the combination with a mandrel supported at its front end, of means for feeding a plurality of strips of stock in laterally spaced relation relative to each other and at an angle substantially less than a right angle relative to said mandrel including friction driven feed rollers common to the strips of stock, said rollers being provided with means for forming a longitudinal groove in one of the stock strips as it is fed, an anvil forming die member having a transversely curved longitudinal die face concentric with said mandrel, a reciprocatingly mounted coacting thrust forming die member having a transversely curved longitudinal die face complementary to the die face of said anvil die member and concentric with said mandrel and against which the strips of stock are impinging fed by said feed rollers, the friction drive of said feed rollers being such as to feed the stock to said forming die members when the thrust die member is in retracted position and slipping when it is in its actuated position, means for actuating said thrust die member in timed relation to the feed of the stock strips, and a follower die member disposed at the rear of said forming die members and through which the work is advanced, said follower die member being provided with supporting rollers for the work.

2. In a machine of the class described, the combination with a mandrel supported at its front end, of means for feeding a plurality of strips of stock in laterally spaced relation relative to each other and at an angle substantially less than a right angle relative to said mandrel including friction driven feed rollers common to the strips of stock, an anvil forming die member having a transversely curved longitudinal die face concentric with said mandrel, a reciprocatingly mounted coacting thrust forming die member having a transversely curved longitudinal die face complementary to the die face of said anvil die member and concentric with said mandrel and against which the strips of stock are impinging fed by said feed rollers, means for actuating said thrust die member, and a follower die member disposed at the rear of said forming die members and through which the work is advanced, said follower die member being provided with supporting rollers for the work.

3. In a machine of the class described, the combination with a mandrel supported at its front end, of means for feeding a plurality of strips of

stock in laterally spaced relation relative to each other and at an angle substantially less than a right angle relative to said mandrel including friction driven feed rollers common to the strips of stock, said rollers being provided with means for forming a longitudinal groove in one of the stock strips as it is fed, an anvil forming die member having a transversely curved longitudinal die face concentric with said mandrel, a reciprocatingly mounted coacting thrust forming die member having a transversely curved longitudinal die face complementary to the die face of said anvil die member and concentric with said mandrel and against which the strips of stock are impinging fed by said feed rollers, the friction drive of said feed rollers being such as to feed the stock to said forming die members when the thrust die member is in retracted position and slipping when it is in its actuated position, means for actuating said thrust die member in timed relation to the feed of the stock strips, work supporting rollers arranged at the rear of said follower die member, and grooved work pull rollers disposed at the rear of said supporting rollers and acting to draw the work through said dies.

4. In a machine of the class described, the combination with a mandrel supported at its front end, of means for feeding a plurality of strips of stock in laterally spaced relation relative to each other and at an angle substantially less than a right angle relative to said mandrel including friction driven feed rollers common to the strips of stock, an anvil forming die member having a transversely curved longitudinal die face concentric with said mandrel, a reciprocatingly mounted coacting thrust forming die member having a transversely curved longitudinal die face complementary to the die face of said anvil die member and concentric with said mandrel and against which the strips of stock are impinging fed by said feed rollers, means for actuating said thrust die member, work supporting rollers arranged at the rear of said follower die member, and grooved work pull rollers disposed at the rear of said supporting rollers and acting to draw the work through said dies while permitting the rotation thereof.

5. In a machine of the class described, the combination with a mandrel, of friction driven means for feeding a plurality of strips of stock in laterally spaced relation relative to each other and at an angle substantially less than a right angle relative to said mandrel, means for forming a longitudinal groove in one of the strips as it is fed, an anvil forming die member having a die face concentric with said mandrel, a coacting thrust forming die member movable relative to said mandrel and anvil die member and having a die face complementary to the die face of said die member and concentric with said mandrel and against which the strips of stock are impinging fed by said feed means, means for actuating said thrust die member, a follower die disposed at the rear of said forming die members and through which the work is advanced, said follower die being provided with supporting rollers for the work, work supporting rollers arranged at the rear of said follower die, and work pull rollers disposed at the rear of said supporting rollers and acting to draw the work through said dies.

6. In a machine of the class described, the combination with a mandrel, of friction driven means for feeding a plurality of strips of stock in laterally spaced relation relative to each other and

at an angle substantially less than a right angle relative to said mandrel, means for forming a longitudinal groove in one of the strips as it is fed, an anvil forming die member having a die face concentric with said mandrel, a coacting thrust forming die member movable relative to said mandrel and anvil die member and having a die face complementary to the die face of said die member and concentric with said mandrel and against which the strips of stock are impinging fed by said feed means, means for actuating said thrust die member, work supporting rollers arranged at the rear of said die, and work pull rollers disposed at the rear of said supporting rollers and acting to draw the work through said dies.

7. In a machine of the class described, the combination with a mandrel, of friction driven means for feeding a plurality of strips of stock in laterally spaced relation relative to each other and at an angle substantially less than a right angle relative to said mandrel, means for forming a longitudinal groove in one of the strips as it is fed, an anvil forming die member having a die face concentric with said mandrel, a coacting thrust forming die member movable relative to said mandrel and anvil die member and having a die face complementary to the die face of said die member and concentric with said mandrel and against which the strips of stock are impinging fed by said feed means, means for actuating said thrust die member, work supporting rollers arranged at the rear of said die, and work pull rollers disposed at the rear of said supporting rollers and acting to draw the work through said dies.

8. In a machine of the class described, the combination with a mandrel, of friction driven means for feeding a plurality of strips of stock in laterally spaced relation relative to each other and at an angle substantially less than a right angle relative to said mandrel, means for forming a longitudinal groove in one of the strips as it is fed, an anvil forming die member having a die face concentric with said mandrel, a coacting thrust forming die member movable relative to said mandrel and anvil die member and having a die face complementary to the die face of said die member and concentric with said mandrel and against which the strips of stock are impinging fed by said feed means, means for actuating said thrust die member, and a follower die disposed at the rear of said forming die members and through which the work is advanced, said follower die being provided with supporting rollers for the work.

9. In a machine of the class described, the combination with a mandrel, of means for feeding

a strip of stock at an angle substantially less than a right angle relative to said mandrel, an anvil forming die member having a die face concentric with said mandrel, a coacting thrust forming die member movable relative to said mandrel and anvil die member and having a die face complementary to the die face of said die member and concentric with said mandrel and against which the strip of stock is impinging fed by said feed means, means for actuating said thrust die member, a follower die disposed at the rear of said forming die members and through which the work is advanced, said follower die being provided with supporting rollers for the work, and work pull rollers disposed at the rear of said follower die acting to draw the work through said dies.

10. In a machine of the class described, the combination with a mandrel, of means for feeding a strip of stock at an angle substantially less than a right angle relative to said mandrel, an anvil forming die member having a die face con-

centric with said mandrel, a coacting thrust forming die member movable relative to said mandrel and anvil die member and having a die face complementary to the die face of said die member and concentric with said mandrel and against which the strip of stock is impinging fed by said feed means, means for actuating said thrust die member, and work pull rollers disposed at the rear of said die member acting to draw the work through said die members.

11. In a machine of the class described, the combination with a mandrel, of means for feeding a strip of stock at an angle substantially less than a right angle relative to said mandrel, an anvil forming die member having a die face concentric with said mandrel, a coacting thrust forming die member mounted for reciprocating movement to and from said mandrel and anvil die member and having a die face complementary to the die face of said die member and concentric with said mandrel and against which the strip of stock is impinging fed by said feed means, and means for reciprocatingly actuating said thrust die member while the stock is being fed by said feed means.

12. In a machine of the class described, the combination of a mandrel of uniform diameter, an anvil forming die member having a longitudinally stepped die face cooperative with said mandrel, a thrust die member cooperative with said mandrel and anvil die member and having a longitudinally stepped die face complementary to the die face of said anvil member, means for feeding strips of stock in laterally spaced relation relative to each other and at an angle substantially less than a right angle relative to said mandrel whereby they are spirally coiled in overlapping joint breaking relation with their edges spaced providing spiral grooves, the outer work strip having a longitudinal groove therein, the rib resulting from the longitudinal grooving of the strip being disposed between the edges of the inner strip, the inner strip constituting a bottom for the groove between the edges of the outer strip, a follower die member disposed at the rear of said forming die members and through which the work is advanced while permitting the rotation thereof, and pull rollers disposed at the rear of said dies to grip the work while it is supported by said mandrel.

13. In a machine of the class described, the combination of a mandrel of uniform diameter, an anvil forming die member having a longitudinally stepped die face cooperative with said mandrel, a thrust die member cooperative with said mandrel and anvil die member and having a longitudinally stepped die face complementary to the die face of said anvil member, and means for feeding strips of stock in laterally spaced relation relative to each other and at an angle substantially less than a right angle relative to said mandrel whereby they are spirally coiled in overlapping joint breaking relation with their edges spaced providing spiral grooves, the outer work strip having a longitudinal groove therein, the rib resulting from the longitudinal grooving of the strip being disposed between the edges of the inner strip, the inner strip constituting a bottom for the groove between the edges of the outer strip.

14. In a machine of the class described, the combination of a mandrel of uniform diameter, an anvil forming die member having a longitudinally stepped die face cooperative with said mandrel, a thrust die member cooperative with said mandrel and anvil die member and having

a longitudinally stepped die face complementary to the die face of said anvil die member, friction feed means for feeding strips of stock in laterally spaced relation relative to each other and at an angle substantially less than a right angle relative to said mandrel whereby they are spirally coiled in overlapping joint breaking relation with their edges spaced providing spiral grooves, the outer work strip having a longitudinal groove therein, the rib resulting from the longitudinal grooving of the strip being disposed between the edges of the inner strip, the inner strip constituting a bottom for the groove between the edges of the outer strip, the thrust die member having a die face against which the strips of stock are impinging fed by said roller, the friction drive of said feed means being such as to feed the stock to said forming die members when the thrust die member is in retracted position and slipping when it is in actuated position, and means for reciprocating said thrust die member to permit feeding of the stock when it is in retracted position and to impart forming thrust to the stock when it is in actuated position.

15. In a machine of the class described, the combination of a mandrel of uniform diameter, an anvil forming die member having a die face cooperative with said mandrel, a thrust die member cooperative with said mandrel and anvil die member and having a die face complementary to the die face of said anvil member, friction feed means for feeding a strip of stock at an angle substantially less than a right angle relative to said mandrel, the thrust die member having a die face against which the strip of stock is impinging fed by said roller, the friction drive of said feed means being such as to feed the stock to said forming die members when the thrust die member is in retracted position and slipping when it is in actuated position, means for reciprocating said thrust die member to permit feeding of the stock when it is in retracted position and to impart forming thrust to the stock when it is in actuated position.

16. In a machine of the class described, the combination of a mandrel of uniform diameter, an anvil forming die member having a die face cooperative with said mandrel, a thrust die member cooperative with said mandrel and anvil die member and having a die face complementary to the die face of said anvil member, friction feed means for feeding a strip of stock at an angle substantially less than a right angle relative to said mandrel, the thrust die member having a die face against which the strip of stock is impinging fed by said roller, the friction drive of said feed means being such as to feed the stock to said forming die members when the thrust die member is in retracted position and slipping when it is in actuated position, a follower die member disposed at the rear of said forming die members and through which the work is advanced while permitting the rotation thereof, and pull rollers disposed at the rear of said supporting rollers to grip the work while it is supported by said mandrel.

17. In a machine of the class described, the combination of a mandrel of uniform diameter, an anvil forming die member having a die face cooperative with said mandrel, a thrust die member cooperative with said mandrel and anvil die member and having a die face complementary to the die face of said anvil member, friction feed means for feeding a strip of stock at an angle substantially less than a right angle relative to said mandrel, the thrust die member having a die face against which the strip of stock is impinging fed by said roller, the friction drive of said feed means being such as to feed the stock to said forming die members when the thrust die member is in retracted position and slipping when it is in actuated position, and means for reciprocating said thrust die member to permit feeding of the stock when it is in retracted position and to impart forming thrust to the stock when it is in actuated position.

18. In a machine of the class described, the combination of a mandrel of uniform diameter, means for feeding a plurality of strips of stock in laterally spaced relation relative to each other and at an angle substantially less than a right angle relative to said mandrel including friction

driven feed rollers common to the strips of stock, said rollers being provided with means for forming a longitudinal groove in one of the stock strips as it is fed, an anvil forming die member having a longitudinally stepped die face cooperative with said mandrel, a reciprocatingly mounted coacting thrust forming die member cooperative with said mandrel and having a longitudinally stepped die face complementary to the die face of said anvil die member and against which the strips of stock are impinging fed by said feed rollers whereby the strips are spirally coiled in superimposed joint breaking relation and with the edges of both strips spaced providing spiral grooves, the grooved strip being the outer strip and the rib resulting from the grooving thereof being disposed between the edges of the inner strip, the groove between the edges of the outer strip being bottomed by the inner strip, the friction drive of said feed rollers being such as to feed the stock to said forming die members when the thrust die member is in retracted position and slipping when it is in its actuated position, and means for actuating said thrust die member in timed relation to the feed of the stock strips.

18. In a machine of the class described, the combination of a mandrel of uniform diameter, means for feeding a plurality of strips of stock in laterally spaced relation relative to each other and at an angle substantially less than a right angle relative to said mandrel, an anvil forming die member having a longitudinally stepped die face cooperative with said mandrel, a reciprocatingly mounted coacting thrust forming die member cooperative with said mandrel and having a longitudinally stepped die face complementary to the die face of said anvil die member and against which the strips of stock are impinging fed by said feed means whereby the strips are spirally coiled in superimposed joint breaking relation, and means for actuating said thrust die member.

19. In a machine of the class described, the combination of a mandrel of uniform diameter, means for feeding a plurality of strips of stock in laterally spaced relation relative to each other and at an angle substantially less than a right angle relative to said mandrel, an anvil forming die member having a longitudinally stepped die face cooperative with said mandrel, said anvil die member comprising a relatively fixed front portion and a rear portion yieldably mounted on the fixed portion and having a die face segment complementary to the portion of the die face on the fixed portion, a reciprocatingly mounted coacting thrust forming die member cooperative with said mandrel and having a longitudinally stepped die face complementary to the die face of said anvil member and against which the strips of stock are impinging fed by said feed means, the die face 60

of said yieldable anvil die member being adapted to receive the stock as it is delivered from said thrust forming die member, and means for actuating said thrust forming die member.

5 20. In a machine of the class described, the combination of a mandrel of uniform diameter, means for feeding a plurality of strips of stock in laterally spaced relation relative to each other and at an angle substantially less than a right angle relative to said mandrel, an anvil forming die member having a die face cooperative with said mandrel, said anvil die member comprising a relatively fixed front portion and a rear portion yieldably mounted on the fixed portion and having 10 a die face segment complementary to the portion of the die face on the fixed portion, a reciprocatingly mounted coacting thrust forming die member cooperative with said mandrel and having a die face complementary to the die face of said anvil member and against which the strips of stock are impinging fed by said feed means, the die face of said yieldable anvil die member being adapted to receive the stock as it is delivered from said thrust forming die member, and means for actuating said thrust forming die member.

15 21. In a machine of the class described, the combination of a mandrel of uniform diameter, means for feeding a plurality of strips of stock in laterally spaced relation relative to each other and at an angle substantially less than a right angle relative to said mandrel, an anvil forming die member having a die face cooperative with said mandrel, said anvil die member comprising a relatively fixed front portion and a rear portion yieldably mounted on the fixed portion and having 20 a die face segment complementary to the portion of the die face on the fixed portion, springs acting to yieldingly support the said yieldable portion of said die member, means for adjusting the tension of said springs, a reciprocatingly mounted coacting thrust forming die member cooperative with said mandrel and having a die face complementary to the die face of said anvil member and against which the strips of stock are impinging fed by said feed means, the die face of 25 said yieldable anvil die member being adapted to receive the stock as it is delivered from said thrust forming die member, and means for actuating said thrust forming die member.
